UNITED STATES PATENT OFFICE.

DAVID T. AUSTIN, OF HOUSTON, TEXAS.

ROAD-SURFACING MACHINE.

Application filed August 25, 1922. Serial No. 584,187.

To all whom it may concern:

Be it known that I, DAVID T. AUSTIN, citizen of the United States, residing at Houston, in the county of Harris and State of Texas, have invented certain new and useful Improvements in Road-Surfacing Machines, of which the following is a specification.

This invention relates to new and useful improvements in a road surfacing machine.

One object of the invention is to provide a machine of the character described specially designed for distributing asphalt, or other similar topping over road surfaces.

Another object of the invention is to provide a machine of the character described, equipped with means for easily cleansing the nozzles, from any material which may tend to harden in said nozzles and clog the same, thus keeping the nozzles at all times clean and open.

A still further feature of the invention resides in the provision of means for utilizing the exhaust from the motor, by which the machine is propelled, for the purpose of cleansing said nozzles, and also for the purpose of increasing the draft through the draft flue.

A still further feature of the invention resides in the provision of an apparatus of the character described which is constructed and arranged in a compact manner and so mounted that it is portable and can be readily moved over the road surface for the purpose of applying the topping, or surfacing material and can be readily moved from one place to another without dismembering any of the parts.

With the above and other objects in view the invention has particular relation to certain novel features of construction, operation and arrangement of parts, an example of which is given in this specification and illustrated in the accompanying drawings, wherein:—

Figure 1 is a vertical sectional view of the apparatus.

Figure 2 is a horizontal sectional view and,

Figure 3 is a rear elevation.

In the drawings the numeral 1 designates the frame or chassis of the truck which is mounted on carrier wheels in the usual manner. The truck is propelled in a conventional manner through the usual motor enclosed by the hood 2. Mounted upon the truck framework there is the furnace 3, pref-

erably formed of sheet metal forming a combustion chamber 4 within which the boiler 5 is mounted. This boiler or tank is provided to contain the surfacing material, the same usually being asphalt or other heavy bitumen which must be heated before it can be spread on the road surface. The tank 5 has the usual manhole 6 through which it may be filled, and leading from the furnace 60 there is the usual smokestack 7. A feed pipe 8 leads from the front end of the tank 5 and passes through the furnace, and at its rear end divides into the branch pipes 9, 9 which enter opposite ends of the nozzle pipe 10. 65 This nozzle pipe is equipped with a plurality of nozzles, any type of nozzle may be employed which may be found most practical, but usually a type of whirling spray nozzle is employed. The feed pipe 8 is equipped 70 with a suitable force pump 12 which is driven from the motor through suitable driving connections, a driving sprocket chain 13 being shown for this purpose. The feed pipe 8 is controlled by suitable valves 75 14 and 15 located near the inlet and discharge ends of said pipe respectively.

It is to be noted that the road surfacing material must be raised to a high temperature before it will be sufficiently fluent for 80 application to the road surface, and it must be delivered through the nozzles under considerable pressure onto the road surface. In order to obtain the best results the nozzles must be kept clean and open so as to not 85 obstruct the free discharge of the heated fluid through them. This is rather difficult for the reason that after the machine has been used if the nozzles are permitted to cool, without first cleansing them of the surfacing material, said material will harden 90 and clog the nozzles, making it very difficult to cleanse them.

For the purpose of cleansing the nozzles I have extended the exhaust pipe 16, leading 100 from the motor and conducted it through the furnace and connected it into the nozzle pipe 10, as shown. This extended exhaust pipe has a gate valve 17, by means of which it may be closed. When this valve is closed the 105 exhaust from the motor passes out through the usual cut out valve, not shown, but in common use.

In operation after each use of the apparatus and before the bitumen hardens in 110 the nozzle pipe the valve 17 is opened and the engine is permitted to run so as to force

the exhaust gases through the nozzle pipe 10 and out through the nozzles 11. These gases are very hot by reason of the fact that the extended exhaust pipe continues through 5 the furnace and the result is that all of the accumulated material in the nozzle pipes and nozzles is thoroughly melted and blown out of said nozzle pipe and nozzles leaving the same clean.

10 There is a return pipe 18 leading out from the rear end of the feed pipe 8 and entering the top of the tank 5. This is controlled by the valve 19, and there is a pipe 20 connecting said feed pipe and return pipe and 15 forming a by-pass. When the exhaust is being used for cleansing out the nozzle pipe and nozzles the valve 15 is turned to close the pipe 8 and the material driven by the pump 12 is forced through the return pipe 20 18 back into the tank. This valve 15, however is open and the valve 19 is closed during surfacing operations permitting the road material to pass freely into the nozzle pipe 10 to be discharged from the nozzles 11.

25 When the valve 15 is turned to open the pipe 8, it closes the by-pass 20 and vice versa. In order to reduce the amount of 30 material delivered onto the road surface, the valve 19 may be partly opened so that a part of the material being pumped through the pipe 8 will be returned to the tank 5 through the pipe 18, and the amount of material delivered to the road surface correspondingly reduced. The arrangement of 35 the valve 15 is such that, when the pump is working, the fluid will always be delivered either through the nozzle pipe to the road surface, or returned back into the tank, thus preventing over strain upon the pump or 40 the bursting of the pump, or the delivery line 8.

Connected into the extended exhaust pipe 16 there is draft pipe 21 extending up

through the draft flue 22 and into the smoke stack 7. This draft pipe is controlled by 45 the valve 23 and when the material is being heated the valve 17 is closed and the valve 23 opened, and an additional draft will thus be created up through said smoke stack thus assisting in the combustion of the fuel in 50 the chamber 4.

What I claim is:—

1. A road surfacing apparatus including a motor vehicle, a furnace thereon, a boiler arranged adjacent the furnace, a nozzle pipe 55 provided with a plurality of nozzles, a delivery pipe connecting the boiler with the nozzle pipe, a pump driven by the vehicle motor and connected with the delivery pipe, and an exhaust pipe leading from the ex- 60 haust manifold of the motor through said furnace and entering the nozzle pipe.

2. The combination with a motor vehicle of a road surfacing apparatus mounted thereon, and including a furnace, a boiler 65 adjacent the furnace, a nozzle pipe formed with a plurality of nozzles, a delivery pipe connected at one end into said boiler and passing through said furnace, and connected at its other end into said nozzle pipe, an ex- 70 haust pipe leading from the exhaust manifold of the motor and passing through said furnace and permanently connected into the nozzle pipe, and means controlling the flow of fluid through said delivery pipe and said exhaust pipe, whereby the exhaust from the motor may be driven alternatively through 75 the smoke-stack and exhaust pipe.

In testimony whereof I have signed my name to this specification in the presence of 80 two subscribing witnesses.

DAVID T. AUSTIN.
